UNITED STATES PATENT OFFICE.

FREDERICK GERKEN, OF NEW YORK, N. Y.

SPARK-PLUG.

1,312,317.

Specification of Letters Patent. Patented Aug. 5, 1919.

Application filed February 26, 1917. Serial No. 150,903.

To all whom it may concern:

Be it known that I, FREDERICK GERKEN, a citizen of the United States of America, and a resident of New York, in the county of 5 New York and State of New York, have invented certain new and useful Improvements in Spark-Plugs, of which the following is a specification.

My invention relates to improvements in 10 so-called "spark-plugs," that is to say, sparking devices employed for igniting the charges of internal combustion engines, and also employed sometimes, in other connections. The improved spark plug herein de- 15 scribed is particularly intended for use in engines in which, either because very high temperatures obtain, or for other reasons, special provision must be made for the cooling of the outer spark terminal of the plug.

20 My invention consists in a novel construction of the outer electrode or sparking terminal of such a plug, whereby, in connection with a particular form of inner electrode or 25 sparking terminal, high sparking efficiency is obtained, coupled with efficient conduction of heat away from said outer sparking terminal. My invention also comprises the means whereby accurate adjustment of the 30 spark gap may be made when desired.

35 The object of my invention is to improve the efficiency of spark plugs of the type described, to insure high sparking efficiency in a plug in which provision is made for rapid conduction of heat away from the outer sparking terminal, and to provide simple and effective means for accurate adjustment of the spark gap.

40 I will now proceed to describe my invention with reference to the accompanying drawings, and will then point out the novel features, in claim, in said drawings:

Figure 1 shows a side elevation of my spark plug;

Fig. 2 shows an end view of the spark 45 plug on a larger scale than Fig. 1;

Fig. 3 shows a fragmentary vertical section of the lower portion of the spark plug, the section being taken on the line 3—3 of Fig. 2;

50 Fig. 4 is an end view, similar to Fig. 2, but showing an alternative construction; and

Fig. 5 is a fragmentary vertical section of the plug shown in Fig. 4, the section being 55 taken on the line 5—5 of Fig. 4.

In the drawings 1 designates the outer

shell of the plug, provided, as usual, with a threaded lower portion 2 adapted to be screwed into the usual spark plug port of an engine. The lower portion of the shell 1 is recessed, as indicated particularly in Fig. 3, and as is common in many spark plugs of the present day. 3 designates one of the sparking terminals or electrodes of the plug, said terminal 3 being an annular member provided with a plurality of slots 4 dividing its lower end into a plurality of projections 5, so that this terminal is of what may be called "castellated" form. 6 designates the other sparking terminal or electrode of the plug having the form of a more or less thin disk, located within, and spaced, as nearly as may be, uniformly away from the projections 5 and supported upon a central post 7.

75 It will be understood that this post 7 is insulated in the usual manner from the shell 1 (8, Fig. 1, designating a portion of the insulating material), and that this post 7 is provided at its upper end with means, such as a screw nut 9, whereby one conductor of an electric circuit may be connected to said post 7. I do not illustrate in detail the structure whereby the post 7 is insulated from the shell 1, as such structure forms no 80 portion of the present invention, and ordinary means for effecting such insulation may be employed.

85 In the operation of the spark plug shown in Figs. 1, 2 and 3, owing to the fact that 90 the central electrode 6 is a smooth-edged disk, all portions of that disk which are opposite or nearly opposite the inner surfaces of the projections 5 are available for the propagation of sparks between projections 5 and said disk 6; and in practice 95 sparks are propagated in broad streams, almost representing or similar to flames, between these projections 5 and the disk 6, the sparks shifting from point to point along 100 the surfaces of the projections 5, such sparks being broad or "fat," as the technical term is, and of extremely high ignition efficiency. Heat imparted to the projections 5 by the 105 hot gases of the engine cylinder is conducted back to the unslotted portion of the ring 3 and thence to the shell of the plug, and thence to the body of the engine cylinder to which that shell is fitted (such body of the engine cylinder being, usually, water-cooled). Owing to the relatively large 110 cross-section of each of these projections 5,

the conduction of heat backward, in the manner described, is extremely efficient, and thereby these projections 5 are kept relatively cool, and so do not tend to produce 5 pre-ignition in an engine cylinder in which, because of high temperatures, or for other reasons, pre-ignition might otherwise be produced.

In the construction herein described, by 10 the employment of a central terminal of disk character, the sparking points are caused to vary widely within the limits of the inner surface of each individual projection 5; also, as above stated, the sparks are 15 broad and "fat". So far as my experience shows, such broad or fat sparks, and such constant varying of point of sparking, is obtainable, when using an outer electrode of castellated form, only by the employment 20 of a central electrode of the nature of a smooth-edged disk, and so far as I am aware, I am the first to employ, in connection with a castellated outer electrode, an inner electrode consisting of a smooth-edged 25 disk.

In some cases it is desired to be able to regulate with accuracy the spark gap between the inner and outer electrodes. In such case I provide the outer electrode with 30 a series of adjustable secondary spark points 10 as shown in Figs. 4 and 5, wherein these secondary spark points have the form of small pointed screws, each carried by one of the projections 5 and each adjustable in that projection 5, toward and 35 from the central spark terminal, here designated by numeral 6^a. It will be obvious that, since each of these spark points 10 is separately adjustable, extreme nicety of adjustment of the spark gaps of the plug may 40 be obtained.

In my application for Letters Patent Serial No. 142,335 filed January 15, 1917, I have illustrated and described a spark plug 45 having an inner disk-terminal provided with openings to permit effective cooling of

that inner terminal, said disk having, however, a smooth outer edge as is the case with the inner spark terminal 6 and 6^a of the present application; and in my application filed February 16, 1917, Serial No. 148,955, I have illustrated and described a spark plug, the inner terminal of which has the form of a ring bent up from wire. Both of these forms of inner electrodes, and similar forms, are to be regarded as disk-terminals within the meaning of the claims of this application; since they are disk-terminals with more or less open centers. 55

Use of the secondary spark points 10 is 60 not, of course, confined to annular terminals of the slotted or castellated structure shown in the drawings of the present application.

What I claim is:

In a spark plug, the combination with an 65 outer spark terminal consisting of an annular member having a number of slots extending axially from one end thereof so as to give said annular member a castellated form, of an inner spark terminal comprising 70 a smooth-edged disk having an edge of appreciable width, and a center rod supporting said disk, there being an open space between the interior of said outer spark terminal and said rod at least equal in width 75 to the diameter of said rod, whereby a space for collection of explosive gas in rear of the inner terminal adequate to maintain a clear gap between said terminals, is provided, said outer spark terminal being provided with secondary spark points, which 80 are screws, the ends of which face the inner spark terminal, which screws may be advanced or retracted individually toward or 85 from said inner spark terminal.

In testimony whereof I have signed this specification in the presence of two subscribing witnesses.

FREDERICK GERKEN.
